CLAIM

(**) Term: **15 Years**

The ornamental design for an imaging system with an NM and CT detector and having illuminated strips, as shown and described.

(21) Appl. No.: **29/540,632**

DESCRIPTION

(22) Filed: **Sep. 25, 2015**

FIG. 1 is a front perspective view of a design for an imaging system with an NM and CT detector and having illuminated strips according to the present invention.

(51) LOC (10) Cl. **24-01**

FIG. 2 is a front view of the imaging system with an NM and CT detector and having illuminated strips of FIG. 1.

(52) U.S. Cl.

FIG. 3 is a back view of the imaging system with an NM and CT detector and having illuminated strips of FIG. 1.

USPC **D24/158**

FIG. 4 is a left side view of the imaging system with an NM and CT detector and having illuminated strips of FIG. 1.

(58) **Field of Classification Search**

FIG. 5 is a right side view of the imaging system with an NM and CT detector and having illuminated strips of FIG. 1.
